[57] **CLAIM**

The ornamental design for irregular octagon solid block rinse additive, as shown and described.

DESCRIPTION

FIG. 1 is a perspective view of the irregular octagon solid block rinse additive of the present invention;

FIG. 2 is a side elevation of the irregular octagon solid block rinse additive of the present invention;

FIG. 3 is a top plan of the irregular octagon solid block rinse additive of the present invention;

FIG. 4 is a front elevation of the irregular octagon solid block rinse additive of the present invention; and,

FIG. 5 is a bottom plan of the irregular octagon solid block rinse additive of the present invention.
